FOREIGN PATENT DOCUMENTS

WO WO2012097328 7/2012

Primary Examiner — Carla J Wright

(57) **CLAIM**

The ornamental design for a phone case, as shown and described.

DESCRIPTION

FIG. 1 is a front view of a phone case showing my new design;

FIG. 2 is a rear view of the phone case;

FIG. 3 is a right side view of the phone case;

FIG. 4 is a left side view of the phone case;

FIG. 5 is a top view of the phone case;

FIG. 6 is a bottom view of the phone case;

FIG. 7 is a bottom front side perspective view of the phone case;

FIG. 8 is a top rear side perspective view of the phone case; and,

FIG. 9 is a bottom front side perspective view of the phone case in use.

The broken lines in FIG. 9 are illustrative of environmental structure forming no part of the claimed design.

1 Claim, 8 Drawing Sheets(56)
